United States Patent Office

Des. 222,039
Patented Sept. 28, 1971

222,039

BUILDING

Doyle T. Vaden, P.O. Box 12192,
Knoxville, Tenn. 37912

Filed Oct. 9, 1969, Ser. No. 19,474

Term of patent 14 years

Int. Cl. D25—04

U.S. Cl. D13—1

FIG. 1 is a perspective front view of my building design;

FIG. 2 is a front view of the building;

FIG. 3 is a rear view of the building, and

FIG. 4 is a top plan view of the same.

The side not shown is like the side shown at the right in FIG. 1.

I claim:

The ornamental design for a building, as shown and described.
